J. VAN BRUNT
TRAVELING CHAIN GRATE

Filed July 4, 1923

BY *Arthur Birnbaum*,
ATTORNEYS

UNITED STATES PATENT OFFICE.

JOHN VAN BRUNT, OF FLUSHING, NEW YORK, ASSIGNOR TO COMBUSTION ENGINEERING CORPORATION, OF NEW YORK, N. Y., A CORPORATION OF NEW YORK.

TRAVELING CHAIN GRATE.

Application filed July 4, 1923. Serial No. 649,390.

My invention relates to traveling chain grates, and has special reference to traveling chain grates of great width which require structural steel supports to carry the weight 5 of the grate between the side frames. As is well known, when a fire is banked in a grate of this character, as heretofore constructed, the portion of the grate bearing the hot coal becomes heated to such an extent that the 10 supporting structure upon which the upper run of the grate rests is liable to become so weakened by over-heating as to cause the entire grate to sag.

The principal object of the present invention is to provide a grate of the character 15 above indicated in which the liability of damage caused by over-heating of the supporting structure of the grate is reduced to a minimum.

20 The following is a description of my invention reference being had to the accompanying drawings, in which,—

Figure 1 is a view in perspective, partly 25 diagrammatical, of a portion of a traveling chain grate structure embodying features of the invention in their preferred form;

Fig. 2 is a transverse sectional view on an 30 enlarged scale, of the transverse girder shown in Fig. 1;

Figs. 3 and 4 are transverse sectional views 35 of supporting beams or girders, on an enlarged scale, each girder constituting a component part of a supporting structure for the upper run of the grate, each view showing a modified form.

The traveling chain grate structure illustrated in the drawings is provided with longitudinally extending side frames 2, a cross beam or girder 4 connecting the side frames, and one or more longitudinally extending 40 beams or girders 6 arranged between the side frames and made in sections having their adjacent ends abutting and secured to opposite sides of the cross girder 4. The girders 4 and 6 are I-shape in cross section, the flanges on the longitudinal edges of the girders being formed by angle irons 10 riveted or otherwise suitably secured to the longitudinal margins of the webs of the girders. A wall 12 is secured at its longitudinal edges on angle irons 14 secured to the side frames 2, respectively, and the wall is further secured to the bottom sides of the girders 4 and 6. The wall 12 constitutes the bottom wall of a wind 45 box which is divided into separate compart-

ments by means of the girders 4, air under pressure being supplied to the separate compartments in the usual manner. Wearing plates or skids 16 and 17 are mounted upon the girder 6, and upon brackets or angle irons 60 20, respectively, secured to the side frames, upon which the upper run 18 of the chain grate slides. A similar wearing plate 22 is mounted on the top of the cross girder 4, this plate being made in sections so as to extend 65 between the plates 16 and 17. The longitudinal edges of the top surface of this wearing plate 22 are rounded over so as not to interfere with the traverse of the grate across it. This wearing plate serves as a sealing plate between the two compartments of the wind box.

In accordance with my invention, means is provided for heat insulating the girders 4 and 6 and the angle irons 20 from the heat of the fuel supporting members of the grate and the fuel supported thereby. In the construction illustrated in Figs. 1 and 2, this heat insulating means comprises a strip or layer 70 80 of asbestos or other heat insulating material which is interposed between each of the wearing plates 16, 17 and 22 and their supports.

The horizontal portions of the angle irons at the upper margins of each girder are provided with upturned flanges 26 between which the layer of insulating material is placed, the flanges 26 serving to hold the longitudinal edges of the layer of asbestos in place. In 85 said Fig. 2 bolts 28 are shown securing the wearing plate 22 to the horizontal portions of the angle irons at the top of the girder, the bolts being omitted in Fig. 1 for convenience 90 of illustration.

In the construction illustrated in Fig. 3, a modified wearing plate 30 is provided having a longitudinally extending channel or recess 32 in its under side that is closed by the top surface of the supporting girder so as to form an air passage extending longitudinally of the plate and girder. This construction enables air or other cooling agent to be directed through the passage, the cooling agent serving as a heat insulating medium between the fuel supporting members of the upper run of the grate and the girder, and also serving to maintain both the girder and the wearing plate at a low temperature.

In the construction illustrated in Fig. 4 the horizontal portions of the angle irons at the 110

- top of the girder are provided with upturned longitudinal edges 34 which are received in a longitudinally extending groove or channel 36 in the under side of a wearing plate 38 so as to form an air chamber or passage between the top of the girder and the wearing plate which may be used for the same purpose as the air passage in the construction illustrated in Fig. 3, as above described.
- 10 In all the forms shown, the protecting means prevent undue heat from injuring the supporting structure, so that even when the fire is banked and normal draft cut off the supporting structure remains relatively cool.
- 15 As will be evident to those skilled in the art my invention permits of various modifi-

cations without departing from the spirit thereof or the scope of the appended claim.

What I claim is:

A traveling grate having, in combination, 20 a supporting structure for the upper run of the grate comprising a girder, a wearing plate upon which the upper run of the grate slides mounted upon said girder, and a layer of heat insulating material interposed between 25 said wearing plate and girder, said wearing plate and girder being so constructed as to extend over the top and bottom sides and longitudinal edges of said layer of heat insulating material.

JOHN VAN BRUNT.
